Primary Examiner — Eric Goodman*Assistant Examiner* — Bao-Yen Nguyen(74) *Attorney, Agent, or Firm* — Bereskin & Parr LLP/S.E.N.C.R.L., s.r.l.(57) **CLAIM**

The ornamental design for a retainer protrusion for a container for food items, as shown and described.

DESCRIPTION

FIG. 1 is an upper perspective view of a retainer protrusion for a container for food items;

FIG. 2 is a left side of the retainer protrusion for a container for food items of FIG. 1;

FIG. 3 is a front view of the retainer protrusion for a container for food items of FIG. 1;

FIG. 4 is a right side view of the retainer protrusion for a container for food items of FIG. 1;

FIG. 5 is a rear view of the retainer protrusion for a container for food items of FIG. 1;

FIG. 6 is a top view of the retainer protrusion for a container for food items of FIG. 1;

FIG. 7 is a bottom view of the retainer protrusion for a container for food items of FIG. 1; and,

FIG. 8 is a lower perspective view of the retainer protrusion for a container for food items of FIG. 1.

In the figures, the broken lines depict portions of the article and form no part of the claimed design.
